UNITED STATES PATENT OFFICE.

GUSTAVE RUNGE, OF CLEVELAND, OHIO.

PRINTER'S INKING-ROLLER.

1,386,427.

Specification of Letters Patent.

Patented Aug. 2, 1921.

Application filed March 5, 1921. Serial No. 449,864.

To all whom it may concern:

Be it known that I, GUSTAVE RUNGE, a citizen of the United States, residing at Cleveland, in the county of Cuyahoga and 5 State of Ohio, have invented certain new and useful Improvements in Printers' Inking-Rollers, of which the following is a specification.

This invention relates to printers' inking 10 rollers and has for an object to provide a roller possessing the requisite or desired resiliency and ink distributing qualities substantially unaffected by climatic conditions and changes.

15 A further object of the invention is to provide an inking roller having a cushioning cylinder of such material as to provide the desired or necessary yielding resiliency substantially unaffected by climatic conditions 20 with an inclosing envelop of material adapted for distribution of ink.

With these and other objects in view the invention comprises certain novel parts, elements, arrangements, compositions, combinations 25 and functions as will be hereinafter more fully described and claimed.

In the drawings Figure 1 is a view of the improved inking roller in side elevation.

Fig. 2 is a view of the improved inking 30 roller in longitudinal diametrical section.

Fig. 3 is a transverse sectional view through the improved roller.

Like characters of reference indicate corresponding parts throughout the several 35 views.

The improved inking roller which forms the subject matter of this application is carried upon a shaft or core 10 which conforms to the press upon which the roller is to be 40 used and the specific disclosure of the core in the drawing is no limitation upon the invention. Upon the core 10 a cylindrical cushion 11 is provided. This cushion 11 is preferably of rubber vulcanized to such a degree as to provide the necessary or desired 45 yielding resiliency of the roller. While rubber has been specified it is intended to include any material or composition which will provide such degree of yielding resiliency as 50 is necessary or desirable in a printers' roller.

As rubber or like compositions is affected by the ingredients of printers' ink and, furthermore, does not properly distribute

ink, an envelop 12 of roller composition is applied to the exterior of the cushion. To 55 wholly protect the cushion from the detrimental effects of the ink it is carried over and wholly incloses the ends of the cushion as indicated at 13, whereby the cushion 11 is wholly inclosed and protected from contact 60 with the ink.

It has been long recognized that an efficient inking roller must possess two major characteristics, namely, yielding resiliency and ink distributing properties. The roller 65 composition of the present date possesses all all of these properties when in prime condition. It is, however, detrimentally affected by climatic conditions rendering the rollers at times inefficient and requiring frequent 70 changes to correspond with the temperature and humidity of the climate.

Rubber has been tried and found to possess the necessary yielding resiliency when properly vulcanized and substantially unaffected 75 by climatic conditions but seriously affected by contact with ink and failing in the proper distribution of the ink upon the form.

Attempts have been made to combine the two but such efforts have failed owing to the 80 incomplete inclosure of the rubber cushion to protect it from contact with the ink. The present invention embodies the yieldingly resilient cushion with the ink distributing envelop wholly enclosing the same. The 85 composition envelop may be of such consistency as to be useful in all climatic conditions depending upon the cushion for its yielding resiliency while presenting such a thin body as to be but little affected by climatic conditions. A single roller will, therefore, serve adequately throughout the year. Furthermore, the composition envelop may be replaced when worn at a minimum expense in view of its very inconsiderable mass. 95

I claim:

1. An inking roller comprising a shaft, a cushion upon the shaft and a coating of ink distributing composition entirely en sealing the cushion. 100

2. An inking roller comprising a cylindrical cushion, composed of material affected by printers' ink, and a wholly en sealing coating of ink distributing composition.

3. An inking roller comprising a shaft, a 105 cylindrical cushion upon the shaft composed

of material detrimentally affected by printers' ink, and a coating of ink distributing composition entirely ensealing the cushion.

4. An inking roller comprising a shaft, a cushion upon the shaft composed of material substantially unaffected by climatic conditions, and a coating of ink distributing composition entirely ensealing the cushion.

5. An inking roller comprising a shaft, a cushion upon the shaft composed of yielding resilient material substantially unaffected by climatic conditions, and a coating of climatically affected ink distributing composition, entirely ensealing the cushion. 10

In testimony whereof I affix my signature.

GUSTAVE RUNGE.
